UNITED STATES PATENT OFFICE.

JOHN J. BRODERICK, OF MANCHESTER, NEW HAMPSHIRE.

PRINTER'S TOOL.

1,087,570.

Specification of Letters Patent.

Patented Feb. 17, 1914.

Application filed December 11, 1912, Serial No. 736,050. Renewed January 17, 1914. Serial No. 812,814.

To all whom it may concern:

Be it known that I, JOHN J. BRODERICK, a citizen of the United States, residing at Manchester, in the county of Hillsboro 5 and State of New Hampshire, have invented a new and useful Printer's Tool, of which the following is a specification.

My invention relates to the subject of printing, and has special reference to tools 10 and appliances that are used by printers to facilitate the art of making up, particularly in newspaper work of this character.

The primary object of the invention is to produce a printer's tool that can be quickly 15 and economically manufactured, and which will materially expedite the operations of justifying columns, putting in and taking out leads, shaving "whiskers" or burs from the ends of linotype slugs, type-high gaging, 20 and stick-holding, the tool being so formed that it is equally adapted for both right and left hand use.

I am aware that separate tools for each of the purposes stated have either been patented 25 or in use for many years, but the multiplicity of tools of this character serves to retard, rather than expedite the work, and in newspaper offices, as well as other printing establishments, it is still the practice to use the 30 finger nails in the operations of removing and inserting the leads, and in shaving the "whiskers" or burs from linotype slug-ends.

In the production of a printer's tool possessing the combination and characteristics 35 stated above, it will be understood that the same may be embodied in other forms, my preferred example of which is shown in the accompanying drawing, wherein like numerals indicate corresponding parts in all 40 the views, and in which:

Figure 1 is a detail view in elevation of the improved tool, Fig. 2 represents the manner of using the tool in putting in a lead in justifying a column, Fig. 3 represents 45 the manner of using the tool as a shaver of the ends of linotype slugs, Fig. 4 represents the manner of use of the tool in gaging the height of set type, and Fig. 5 represents the use of the tool as a stick-holder.

My improved printer's combination tool is preferably formed from a single sheet of material, such as steel, brass or the like, the body 1 being thin and perfectly flat, having 55 an elongated and straight base edge 2, two and one-sixth inches in length, correspond-

ing with the standard width of newspaper columns, or 13 ems pica, which may or may not be graduated. The opposite edge of the body 1 has its corners cut away, as indicated by the numerals 3, 3, to provide oppositely disposed "shavers," which are specially adapted for use in removing or shaving "whiskers" or burs from the end of linotype slugs. In this connection, it will be apparent that by disposing the shavers on the opposite ends of the body 1, the tool need not be reversed for either right or left hand use. The upper edge of the body 1, between the two shavers 3, 3, is provided with the 60 longitudinal recess 4, intended for use as a type-high gage, being 916/1000 of an inch in length. At one end of the recess 4, is a vertical slot, which extends transversely of the body 1, the slot opening into the said recess 65 and serving as a stick-holder, either one of the shavers serving as a base, as illustrated in Fig. 5.

The improved tool being of such form that it can be made from a single sheet of metal 80 or other material, it can be made by a single operation of a stamping or punching machine, which quickly and economically produces the tool.

The vertical, transverse slot in the base of 85 the recess, intended to engage the stick in the stick-holding operation, may be cut of the proper width to serve as a plate gage, and other uses may suggest themselves to printers, or to those skilled in this particular art.

In my illustrated preferred form of this combination tool, the base portion is in the 90 form of a rectangle, and the upper portion in the form of a regular trapezoid, the base line of which is of the same length as the 95 length of the rectangle, and the top portion of which is recessed longitudinally, and vertically slotted at one end of said recess. This particular form lends itself to convenient holding in the palm of the hand in the making-up operation, ready for instant use for either of the purposes named.

Each of the separate elements composing this combination tool, is more or less dependent upon the other elements in practical operation, the shaver, for instance, forming the base of the stick-holding element.

Having fully described my invention, and its several uses, I claim:—

1. A printer's combination tool, comprising 110 a thin, flat body portion, having a straight base edge, and an upper edge with

its corners cut away, said upper edge being longitudinally recessed between the said corners, and said body portion being provided with a transverse slot opening into said recess.

2. A printer's combination tool, comprising a body portion having the corners of one longitudinal edge cut away, said longitudinal edge portion between said corners 10 being provided with type-gaging and stick-holding means.

3. A printer's combination tool, comprising a rectangular body portion, having the corners of one longitudinal edge cut away 15 to form shaving means, and between said corners a longitudinal recess, forming type-gaging and stick-holding means.

4. A printer's tool, comprising a thin, flat, longitudinal body portion, having a 20 straight edge adapted to serve as a make-up rule, the opposite edge of said body portion having a longitudinal recess adapted to serve as a type-high gage, a slot in said recess adapted to serve as a stick-holder, and corners cut away to form slug-shavers.

5. A printer's tool, comprising a single piece of thin, flat metal, rectangular trapezoidal in shape, having a straight base edge, and a top, oppositely disposed edge having 30 a central longitudinal recess, and a vertical slot in one end of said recess, extending downwardly into the body portion.

6. A printer's tool, consisting of a single piece of sheet metal, rectangular trapezoidal 35 in shape, and comprising in its base portion

a make-up rule for justifying newspaper columns, and in its top portion a type-high gage and a stick-holder, and in its top end portions inclined edges adapted to shave the burs from the ends of linotype slugs.

40

7. A printer's tool, adapted to be struck from sheet metal, and comprising in combination a rectangular make-up rule, and in the top, trapezoidal extension of said rule, a longitudinally disposed recess for gaging 45 the height of type, a transverse slot in said recess, extending downwardly into the body of said tool for holding a stick, and inclined end edges for shaving the ends of linotype slugs.

50

8. A printer's tool, stamped from sheet metal in a form combining a rectangle and a trapezoidal top extension thereof, and comprising in said rectangle a make-up rule, and in said top extension a type-high gage, 55 a stick-holder, and shavers for removing the burs from the ends of linotype slugs.

9. As a new article of manufacture, a printer's combination tool, adapted to be stamped from sheet metal, and comprising 60 a rectangular make-up rule, and a substantially trapezoidal extension thereof, having means for type-height gaging, stick-holding, and shaving the ends of linotype slugs.

JOHN J. BRODERICK.
